(57) **CLAIM**

The ornamental design for a sofa, as shown and described.

DESCRIPTION

FIG. 1 is a front, right, top perspective view of a sofa, showing my new design;

FIG. 2 is a rear, left, bottom perspective view thereof;
FIG. 3 is a front elevational view of the enlarged scale
thereof;

FIG. 4 is a rear elevational view of the enlarged scale
thereof;

FIG. 5 is a left side view of the enlarged scale thereof;

FIG. 6 is a right side view of the enlarged scale thereof;

FIG. 7 is a top plan view of the reduced scale thereof;

FIG. 8 is a bottom plan view of the reduced scale thereof;

FIG. 9 is a front, right, top perspective view thereof in an
alternate configuration;

FIG. 10 is a front, right, top perspective view thereof in an
alternate configuration;

FIG. 11 is a front, right, top perspective view thereof in an
alternate configuration;

FIG. 12 is a front, right, top perspective view thereof in an
alternate configuration;

FIG. 13 is a front, right, top perspective view thereof in an
alternate configuration;

FIG. 14 is a front, right, top perspective view thereof in an
alternate configuration;

FIG. 15 is a front, right, top perspective view thereof in an
alternate configuration;

FIG. 16 is a front, right, top perspective view thereof in a
detached state; and,

FIG. 17 is an enlarged view of detail 17 in FIG. 16.

The dashed broken lines in the figures are for the purposes
of illustrating portions of the sofa and form no part of the
claimed design.

The dash-dot-dash broken lines are for notating enlarged
views and form no part of the claimed design.

1 Claim, 17 Drawing Sheets
